UNITED STATES PATENT OFFICE.

EDWARD STROSCHEN, OF OSHKOSH, WISCONSIN.

SELF-ADJUSTING ROTARY BRUSH.

1,290,403.

Specification of Letters Patent.

Patented Jan. 7, 1919.

Application filed December 12, 1917. Serial No. 206,747.

To all whom it may concern:

Be it known that I, EDWARD STROSCHEN, a citizen of the United States, and resident of Oshkosh, in the county of Winnebago and 5 State of Wisconsin, have invented certain new and useful Improvements in Self-Adjusting Rotary Brushes; and I do hereby declare that the following is a full, clear, and exact description thereof.

10 My invention relates to certain new and useful improvements in carpet sweepers and refers particularly to the manner of journaling the friction pulley and connecting the rotary brush with the friction pulley.

15 In devices of this character now in vogue, the friction pulley is rigidly connected with the rotary brush and the brush and pulley are both capable of vertical movement, a spring or other means being employed to 20 normally urge the same downwardly, but this method of permitting vertical adjustment of the rotary brush is very objectionable in that the relation of the friction pulley with respect to its drive wheels is continuously 25 changing with every vertical movement of the brush, and hence with this inherent objection in view my invention has for its primary object to provide a carpet sweeper having a permanently journaled friction 30 roller and a self adjusting rotary brush driven thereby.

A further object of the present invention is to provide a self adjusting rotary brush having a detachable universal joint driving 35 connection with its friction pulley and adapted to rest against the floor surface by gravity.

A still further object of the present invention is to provide means for permitting 40 vertical adjustment only of the rotary brush.

With the above and other objects in view which will appear as the description proceeds my invention resides in the novel construction, combination and arrangement of 45 parts substantially as hereinafter described and particularly defined by the appended claims, it being understood that such changes in the precise embodiment of the 50 herein disclosed invention may be made as come within the scope of the claims.

In the accompanying drawings I have 55 illustrated one complete example of the physical embodiment of my invention constructed according to the best mode I have

so far defined for the practical application of the principles thereof, in which:

Figure 1 is a side elevational view of a combined carpet sweeper and vacuum cleaner equipped with my invention. 60

Fig. 2 is a view partly in section and partly in elevation the same being taken on the plane indicated by line 2—2 of Fig. 1, and

Fig. 3 is a view part in section and part 65 in elevation taken on the plane indicated by line 3—3 of Fig. 2.

Referring now more particularly to the accompanying drawings, in which S represents a combined carpet and vacuum cleaner 70 which may be of any well known make or construction, and each side wall thereof has secured thereto by means of suitable fastenings 1, a plate 2 in which are journaled the usual drive wheels 3 having their peripheries coated with rubber or other suitable substances, and fixed to the plate 2 by means of its inner flange portion 4 is a sleeve 5 upon which is rotatably mounted the bushing 6 of a friction pulley 7, the usual 80 guard rails 8 being provided to protect the drive wheels and friction pulley. 75

The sleeve 5 terminates a little inwardly of the outer end of the bushing 6, which is formed with the inwardly projecting portion or enlargement 9, and extending transversely across the central opening of the sleeve 5 at its outer end is a pin 10 engaging an opening 11 provided in the outer end of a spindle 12 which has its inner end slotted 90 or bifurcated as at 13 and passed into a recess 14 in the end of a rotary brush 15 and detachably engaging a pivot pin 16 passing through the recess 14. 85

The opening 11 of the spindle 12 has its 95 ends curved or flared, as best shown in Fig. 2, whereby a universal joint connection is provided between said spindle and bushing 6. By this method of connecting the brush 15 with friction pulley 7, the 100 brush is capable of vertical adjustment without changing the relation of the friction pulley with respect to its drive wheel 3, and to prevent lateral movement of the brush 15 the ends thereof are confined between a 105 pair of guide members 17 secured to the inner side of the plates 2 juxtaposed the opening 18 therein alining with the recess 14 and the bore of sleeve 5.

From the foregoing description taken in 110

connection with the accompanying drawings it will be readily apparent that the brush 15 rests by gravity upon the cleaning surface and is readily capable of vertical adjustment to accommodate any irregularities in the cleaning surface, and that the manner of connecting the spindle 12 with the brush permits the ready detachment of the same.

While in the accompanying drawings I 10 have illustrated the same as in use with a combined carpet sweeper and vacuum cleaner, it will be understood that I do not desire to limit the use of my device upon a combined carpet sweeper and vacuum 15 cleaner, but that the same may be readily used upon any form of carpet sweeper.

I claim:

1. In a device of the class described, the combination with a drive wheel, of a friction 20 pulley rotatably mounted adjacent said drive wheel and adapted to be rotated thereby, a rotary brush, a spindle connecting said friction pulley and rotary brush, said spindle having a universal joint connection with 25 said pulley and a slidably and pivotal con-

nexion with said rotary brush, and means for preventing lateral movement of said brush.

2. In a device of the class described, the combination with a drive wheel, of a sleeve 30 secured adjacent said drive wheel, a friction pulley journaled upon said sleeve and adapted to be rotated by said drive wheel, a rotary brush having its end recessed in line with the bore of said sleeve, a spindle having one 35 end disposed in the recess of said rotary brush and slidably and pivotally connected therewith, the other end of said spindle being disposed in the bore of said sleeve and connected by a universal joint with said 40 friction pulley, and means engaging the end of said rotary brush whereby to prevent lateral movement thereof substantially as described.

In testimony that I claim the foregoing I 45 have hereunto set my hand at Oshkosh, in the county of Winnebago and State of Wisconsin.

EDWARD STROSCHEN.
